UNITED STATES PATENT OFFICE

STANLEY H. HOBSON, OF ROCKFORD, ILLINOIS, ASSIGNOR TO GEO. D. ROPER CORPORATION, OF ROCKFORD, ILLINOIS, A CORPORATION OF ILLINOIS

DESIGN FOR A PANEL FOR A RANGE OR SIMILAR ARTICLE

Application filed October 9, 1931. Serial No. 41,350. Term of patent 7 years.

To all whom it may concern:

Be it known that I, STANLEY H. HOBSON, a citizen of the United States, residing at Rockford, in the county of Winnebago and State of Illinois, have invented a new, original, and ornamental Design for a Panel for a Range or Similar Article, of which the following is a specification, reference being had to the accompanying drawing, forming part thereof.

The drawing is a perspective view of the

panel, showing the thickness. The surface ornamentation consists of irregular lines of a color contrasting with the background color. This panel is sold as an article of manufacture.

I claim:

The ornamental design for a panel for a range or similar article, substantially as shown and described.

STANLEY H. HOBSON.
